CONCRETE FORM MATERIAL

Richard D. Behm, Vancouver, Wash., assignor to
M and M Wood Working Company, Portland,
Oreg., a corporation of Oregon

Application October 28, 1941, Serial No. 416,854

2 Claims. (Cl. 25—131)

The present invention relates to concrete forms, and more particularly to materials to be used in the construction of such forms.

Concrete usually is poured in a semi-fluid state into forms in which it sets and hardens, after which the forms are removed and the concrete allowed to cure. The forms usually are constructed of lumber which is secured in place and braced by an outer framework of timbers. Upon the removal of forms of the usual construction, the surface of the concrete which was in contact with the inner surface of the form is not smooth, but is pitted with a great number of small craters or cavities formed by bubbles of air and water which were present in the mix before it set. The problem has been to eliminate these craters and cavities, which commonly occur in all concrete surfaces. In exterior walls water seeps into the surface cavities and, upon freezing, causes further disruption of the surface and exposes additional cavities, tending toward a shortened life of the structure. In ordinary commercial construction, in order to improve the appearance and also the weathering strength of the wall, it is common practice to provide a stucco coating which, however, adds appreciably to the cost of the finished structure. On dams, spillways, and similar projects, the surface openings must be filled, since on such projects, if the concrete is not properly finished, it is subject to considerable wear.

When the concrete mixture is made it is necessary to add water in sufficient quantity so that the mass will be fluid enough to pour and flow to all parts of the form. The cement in the concrete combines with only a part of the water. The remainder of the water is present only to give the mass fluidity. This water is necessary only to facilitate mechanical handling of the concrete. Concrete undergoes an initial setting reaction within a relatively short time after it is poured, at which time the excess water, i. e., that portion of the water which does not combine with the cement, is given up and accumulates as globules, particularly at the surface of the form. When the usual type of wooden forms is used, this excess water will be observed to drain out through the cracks between adjacent boards, or eventually be absorbed into the wood itself, leaving small craters or cavities in the surface of the concrete.

Applicant has discovered that if the form is lined with an absorbent material and the concrete is poured against this absorbent surface, then, when the form is stripped away, the surface

of the concrete is free from craters and surface cavities. The globules of water which are the cause of craters and surface cavities are eliminated by absorption into the absorbent lining. Furthermore, it has been found that the surface of the concrete is appreciably harder and stronger than when it is poured against a nonabsorbent surface. This is of great value because it improves tremendously the wearing surface of the concrete structure.

In accordance with one form of the invention, a base member such as a sheet of plywood is provided on one surface with a layer of highly moisture absorptive material. Concrete forms are built of this material with the absorptive layer on the inside of the form, which layer rapidly withdraws the free water out of the mixture, filters the cement from the water, and leaves a remarkably smooth, hard surface after the cement has set. Accordingly, the surface of concrete structures made with forms of this material is smooth and of unusual density, and of great mechanical strength.

It is an object of the present invention, therefore, to provide a new and improved material for making concrete forms which will produce a surface on the concrete structure substantially smooth and free of surface irregularities.

More especially, it is an object of the invention to provide a new and improved material for making concrete forms which will absorb free water from the layer of concrete next adjacent thereto, leaving the concrete surface substantially smooth and without surface cavities.

It is a further object of the invention to provide a new and improved laminated material for making concrete forms which will produce a surface on the concrete which is of high mechanical strength and extremely weather resistant.

It is a further object of the invention to provide an improved material for making concrete forms which is productive of a concrete structure appreciably harder and stronger than concrete poured in forms heretofore in use, and which possesses a greatly improved wearing surface having a high degree of strength and hardness.

With these and other objects and advantages in mind, the invention resides in the structure hereinafter described and illustrated in the drawing, it being understood that various changes in form, proportion and details of construction within the scope of the appended claims may be resorted to without departing from the spirit or

sacrificing any of the advantages of the invention.

In the drawing:

Figure 1 is a cross sectional view through a section of a concrete wall being constructed with the aid of forms made of material according to the present invention.

Figure 2 is a fragmentary view in perspective of concrete form material embodying the invention, portions thereof being broken away for greater clarity.

Figure 3 is a perspective view of a portion of a concrete form making material showing a modification of the structure illustrated in Figure 1.

Figure 4 is a cross sectional view of a concrete wall being constructed in accordance with a customary procedure, and which is explanatory of the objects of the present invention.

Figure 5 is a fragmentary sectional elevation of a concrete form making material according to a modification of the invention.

In order to impart a dense smooth surface to the concrete, it is necessary, as a first consideration, that the wet mix contain such an excess of water that the mix, when poured, will flow readily to all parts of the form, leaving substantially no voids or air pockets therein. However, this excess water is somewhat detrimental to the strength of the mass when it is finally set, and the excess or free water should be removed from at least the layer of concrete next adjacent the form within the short period of time after the mix is poured and before setting takes place. In the structure embodying the invention, the excess water is effectively removed by the provision of extremely fine drainage apertures in a readily wettable material at the surface of the form so that water will pass quickly therethrough without carrying any cement with it. This absorbent material at the surface of the form acts as a filter so that no cement is lost from the mix. When the wet concrete flows into contact with the absorbent lining of the form, the lining immediately absorbs free water into itself, as well as any air bubbles which have become occluded in the mixture, and leaves a remarkably smooth and hard surface after the cement has set. By thus absorbing away some of the free water, the absorbent form lining increases the strength of the concrete adjacent the surface; and it is at the surface of the structure that increased strength and hardness are most useful, both from the standpoint of structural strength and of wearing quality.

In accordance with the present invention, I provide concrete form making material comprising a relatively rigid base unit such as, for example, a sheet of plywood having a plurality of plies of wood veneer adhesively secured interfacially, and in which the grain of each ply is disposed across the grains of adjacent plies. To one side of the base member is secured a relatively thin sheet of moisture absorptive material. Referring to the drawing, the form for the concrete wall 10 is formed by a pair of spaced sheets of form making material, each consisting of a base portion 12 which, in this instance, is a three-ply plywood panel having suitably secured to one side thereof layers 13 of moisture absorptive material. The number of plies for the laminated base portion 12 will, of course, depend upon the necessary mechanical strength required of the form, taking into consideration the spacing of the framework timbers, the thickness of the wall to be built, and other factors. In the modification

in Figure 3 the base portion 12' comprises a five-ply plywood panel, though it will be obvious that the number of plies and hence the thickness of the base portion may be varied as desired.

The lining 13 may be of any absorptive material, it being preferred, however, that the outer surface thereof be substantially smooth, that is, having few if any fibers extending outwardly therefrom which might become imbedded in the cement and interfere with the clean removal of the form from the structure after the concrete has hardened. One material which has been found suitable for use as an absorbent lining is a felted material made of scrap paper and ground wood, commonly known as chip board. It is preferred that the surface of the felt be calendered to produce a substantially smooth and close textured surface, although it may be desirable to use material having textured finishes on the absorbent lining which would be transferred to the surface of the completed structure.

A high degree of absorptiveness is required to produce the best results. However, the surface against which the concrete is poured should not be very greatly compressible for the reason that the concrete is poured against this surface with considerable force and dents might otherwise be made by rocks contained in the concrete which would destroy the smoothness of the concrete after it has set. For this reason the thickness of the absorptive lining should be of the order of one-eighth to one-fourth inch, it having been determined that a lining of this thickness mounted upon a rigid base portion is only slightly compressible even though water soaked. An absorptive lining of such material and of such thickness will rapidly absorb free water from the layer of wet concrete next adjacent thereto to a depth of about one-half inch. This absorption takes place within the first few seconds after the concrete has been poured, and the water which has been absorbed into the lining will rapidly be replaced by fluid concrete before the setting action occurs. It is important that the outermost surface of the absorptive lining be of fine texture so as to substantially filter cement from the water being absorbed thereby. This filtered layer of cement next adjacent the form provides an extremely hard layer over the outer surface of the finished wall. Tests show that the concrete hardened with an absorbent lining such as herein disclosed is appreciably stronger than concrete poured into forms of ordinary construction; and is more resistant to deterioration by freezing.

The absorptive lining 13 is preferably adhesively secured to the plywood base panel 12, and the adhesive employed to secure the lining should permit the transfer of water from the absorptive lining to the base member. The adhesive coating between the plywood base 12 and the absorptive lining 13 is indicated at 14 in Figure 2, and preferably may consist of a solution of silicate of soda, commonly known as water glass. After the original absorption of moisture from the wet mix by the absorptive lining 13, the moisture from the lining is gradually transferred through the glue line to the wooden base member 12, and the absorptive lining is rendered capable of absorbing additional water liberated during the second stage of the chemical change in the concrete.

It will be appreciated that in the structure embodying the present invention, each of the laminations is coextensive with each of the other laminations in the structure, and that, due to the relatively large size of the panels used in mak-

ing concrete forms, the finished wall will be substantially free of surface irregularities.

In Figure 4 is illustrated the construction of a concrete wall with the aid of forms utilizing shiplap as the material against which the concrete is poured. The excess water in the wet mix may to some extent escape from such forms at the joints between adjacent pieces of shiplap, but none of the cement is filtered from the water, and it is not uncommon to find the lapped edges of such form material filled with cement after the concrete has hardened. Also illustrated in Figure 4 is the manner in which water pockets are formed in the surface of the concrete wall. There is illustrated globules of water 15 lying in contact with the wooden forms 16. Eventually this water is absorbed into the wood, but not until after the initial setting action has taken place. The escape of the water globules 15 leaves cavities and craters in the surface of the concrete wall and beneath these exposed cavities are additional cellular cavities 17 formed by water globules formed at the time the concrete was poured and from which the water has since evaporated from the wall. During the winter seasons the outer cavities becomes filled with water, which, upon freezing, disrupts the surface and exposes cavities lying therebeneath, thus materially shortening the life of the structure.

In Figure 5 is illustrated a laminated concrete form material comprising a relatively rigid base unit of corrugated iron 18, to one side of which is secured a sheet of moisture absorptive material 19. This modification is particularly useful when it is desired to impart a fluted surface to the finished wall structure.

After the concrete has hardened to the desired degree, the forms may readily be stripped therefrom, the absorptive lining being substantially non-adherent to the concrete surface. By the use of the concrete form material herein described, the finished wall will be substantially free of surface depressions or cavities such as heretofore have been caused by water pockets. The entire surface of the finished wall will be covered with an extremely dense layer of cement which was filtered from the water absorbed by the absorptive lining, and the wall structure to a depth

of the order of one-half inch or more will be substantially free of voids, thus producing exceptionally high mechanical strength resulting from a condition analogous to case hardening. Moreover, the surface of the wall produced by forms constructed in the manner described possesses a smoothness equivalent to that of a trowelled plaster surface and may be tinted or painted as desired.

Having now described my invention and in what manner the same may be used, what I claim as new and desire to protect by Letters Patent is:

1. A concrete form member consisting of a plywood base member having an absorptive plurality of plies of wood veneer adhesively secured interfacially, and a single lamination of relatively thin highly absorptive material secured to one surface of said plywood base member, a layer of moisture permeable, water insoluble adhesive securing said absorptive material to said base member throughout the areas of the contacting faces thereof each of said laminations of said material being coextensive with each of the other of said laminations, said absorptive material being placed to engage the surface of concrete poured into said form for absorbing water directly therefrom.
2. A concrete form member consisting of an absorptive plywood base member having a plurality of plies of wood veneer adhesively secured interfacially, and a single lamination of relatively thin, highly absorptive material secured to one surface of said plywood base member and placed to engage the surface of concrete poured into the form for absorbing moisture directly therefrom, said base and lamination of absorptive material being secured together by a layer of moisture permeable, water insoluble adhesive which secures said absorptive material to said base member throughout the area of the contacting faces thereof, said thin layer of material and the base being coextensive with each other and the thin layer being provided with a calendered surface having extremely fine apertures therethrough for filtering cement from water absorbed by said material.
